UNITED STATES PATENT OFFICE

139,947

DESIGN FOR A BELT OR SIMILAR ARTICLE

Sylvia Saponoff, New York, N. Y.

Application August 17, 1944, Serial No. 114,906

Term of patent 3½ years

(Cl. D3—10)

To all whom it may concern:

Be it known that I, Sylvia Saponoff, a citizen of the United States of America, residing in New York city, county of Kings, and State of New York, have invented a new, original, and ornamental Design for a Belt or Similar Article, of which the following is a specification, reference being had to the accompanying drawing, forming part thereof, wherein,

Figure 2 is a similar view thereof showing the belt or similar article in an open position.

I claim:

The ornamental design for a belt or similar article, substantially as shown.

SYLVIA SAPONOFF.
